UNITED STATES PATENT OFFICE.

JAMES G. DUDLEY, OF NEW YORK, N. Y.

AWNING CASEMENT WINDOW.

Application filed October 19, 1921. Serial No. 508,714.

This invention relates to windows, and particularly to that class of windows known as casement windows.

The object of the invention is to produce a window with a full opening of the window area for the purpose of free ingress and egress of air for ventilation, and at the same time to prevent the ingress of water during storms.

10 A further object is to provide a window that can be readily converted into an awning without trouble or loss of time, and without opening the window and reaching outside the same.

15 Another object is to provide a window where all pulleys, weights, weight pockets and cords are eliminated, doing away with the liability of the weights jamming, or the cords being cut by the pulleys, as well as 20 the expense thereof.

Still another object is to provide a window in which each section both inside and out can be readily cleaned from the inside of the room.

25 With these objects in view my invention consists in certain novel features of construction and in certain parts and combinations hereinafter to be described and then more particularly pointed out in the claims.

30 The conventional double hung sash as is well known is apt to get out of order, sticks, jamming at the wrong moment, the weights rattle in the weight pockets, and cords by constant running backwards and forwards 35 over the pulleys wear and tear and finally break, and the window is practically useless, and it should be remembered that there are four of each of these weights, cords and pulleys to each double hung sash window.

40 Besides when one of the sashes is fully open the other must necessarily be closed, and therefore there is but one half or fifty per cent of the window available for ventilation or view.

45 However in the present invention all of these negative points are obviated; for by making the window in three parts and having all of the said parts hinged,—the top part of the lintel, and the two side members 50 to the jambs,—all weights, cords and pulleys are done away with. The said three parts being pushed out at a ninety degree angle give not one half, but full ventilation,—one hundred per cent. Also an unobstructed 55 view.

By bringing the top member to an angle

of say forty-five degrees the window can still be left one hundred per cent open and get all of the benefits of good ventilation even more than with the double hung sash 60 window, and with the added advantage that it will keep out the rain and the snow; for the angularly placed top sash will cover the opening sufficiently to prevent the rain and the snow from entering. Also the hinged 65 side casements prevent the winds blowing from the sides entering directly into the room.

By attaching a shade roller with shade to the inside of the upper sash the same 70 results are obtained which are secured from the conventional fabric awning shade on the exterior of the window. Of course inside shades or curtains can also be attached to the lower wings or casements.

75 Window screens can readily be applied to the room side in any desirable conventional fashion; either as two shifting halves, or as two wings hinged at the vertical edges and made to swing inwardly, or as a center folding and horizontally sliding combination, or in any other fashion desired. Also simple weather stripping may be easily applied to the invention so as to render the same tight 80 against wind and weather.

85 In the accompanying drawings, in which the same numerals of reference refer to similar parts throughout the several views:

Figure 1 is a front elevation of the preferred form of my awning casement window. 90

Fig. 2 is a sectional view taken on the line A—B of Fig. 1.

Fig. 3 is a plan view of Fig. 1, but showing the window wide open.

Referring now to these drawings: 1 is the ordinary window frame which may have any desired ornamentation or be plain as shown, 2 is the swinging or vertically moving sash or awning casement; 3 is either of the lower swinging or horizontally moving or wind deflecting sashes or casements or wings. Both of these lower sashes as well as the upper one may comprise one pane of glass or many as shown. 4 are the hinges. 5 indicates means, or hardware fixtures with handles 6 all of conventional or special form that may be attached to the window members to assist in swinging each of the three leaves or sashes or casements open or shut and rigidly holding the same in any desirable position from the closed position or zero degrees as shown in Fig. 1 more particularly, 100 105 110

to wide open position or ninety degrees from said closed position, shown more particularly in Fig. 3.

The inner faces 7 of the four sides of the

- 5 upper sash 2 make flat contact respectively with the top and side window stop beads 8 and 9 respectively, and with the top face of the outer side 10 of the two lower wings 3. In like manner the inside of the bottom 10 face 11 and the right and left faces 12 of each of the lower wings 3 make flat contact respectively with the window stool 13 and the side stop beads 14; while the central vertical dividing inner faces or edges 15 of 15 the two lower casements or wings 3 make contact by a suitable rabbeted joint 16, or in any other manner desired.

A shade roller 17 with shade 18 and catch 19 is attached to the upper sash 2.

- 20 The operation of the invention is substantially and preferably as follows: It will be seen that when closed the window is as tight and safe as any heretofore invented, and does not differ so much therefrom. 25 But as soon as the same is opened the great difference is at once apparent. For now if the room is to be ventilated all of the leaves are thrown open at once to the full extent of the opening in the wall as in Fig. 3, and ventilation takes place very rapidly; while 30 as aforesaid in the conventional or regulation double hung sash, only one half of the opening can be utilized for this purpose. The single sash casement can do the same; 35 but in this latter case should a storm come up, either the rain pours in, in case the casement is left open, or if it be closed and it certainly must be, all ventilation is cut off.

But with the herein-described invention

- 40 these troublesome points are obviated, for by letting down the upper sash to say forty five degrees as shown in Fig. 2 the rain will be kept out and yet the room will be well ventilated.

- 45 This however is not the case with other casement windows having a transom above the hinged members; for the transom is so small in length and overhangs the open casement to such a small extent that when 50 open it is of no use against a storm, and in fact is no better than the said regulation double hung sash, for if the lower sash be left open the rain will come into the room. But by making the upper hinged sash the 55 full size of a window sash of the double hung sash window, and the lower casement

split in two and both open outwardly, each of the three leaves might be left open without rain coming in while yet good ventilation is secured.

If the sun is shining into the room too brightly, the shade on the upper sash can be drawn down across the same, making an awning out of the said upper sash having all of the good points of the ordinary fabric awning hung on the outside of the window, without the trouble of reaching outside the window to adjust the said awning.

When the herein described window is wide open a clear and unobstructed view can be obtained, there being no ugly check rail or middle horizontal bar right across the middle of the window; for no matter whether the upper or the lower sash of the regulation window is open the said rail is always present and not only limits the view but detracts therefrom, while in the present window when the same is open there is a clear and unobstructed view.

Certain preferable details of construction have been shown and described but I do not limit myself to details, as it is obvious that many changes may be made in the arrangement of the several parts and the said details of construction without departing in any manner from the spirit of my invention.

I claim:

1. In combination, a window frame and upper and lower windows therein, the said lower window hung to swing upon a vertical axis and the said upper window hung to swing upon a horizontal axis, and stops for the said upper and lower windows, the stops for the said lower window being inset beyond the stops for the said upper window.

2. In combination, a window frame and upper and lower windows therein, the said lower windows hung to swing upon vertical axes and the said upper window hung to swing upon a horizontal axis, the said upper window when closed overlapping the upper parts of the said lower windows and holding the same closed, all of the said windows being entirely within the said frame when closed and adapted when open to present an unobstructed passage for air through the said window frame, and stops for the said upper and lower windows, the stops for the said lower windows being inset beyond the stops for the said upper window.

JAMES G. DUDLEY.
